UNITED STATES PATENT OFFICE.

PETER CHATELAIN, OF BOSTON, MASSACHUSETTS, ASSIGNOR TO M. H. DRYFOOS & CO., OF SAME PLACE.

DESIGN FOR A GLOVE.

SPECIFICATION forming part of Design No. 25,049, dated January 14, 1896.

Application filed December 13, 1895. Serial No. 572,091. Term of patent 14 years.

To all whom it may concern:

Be it known that I, PETER CHATELAIN, of Boston, in the county of Suffolk and State of Massachusetts, have invented and produced 5 a new and original Design for Gloves, of which the following is a specification, reference being had to the accompanying drawing, which shows a glove embodying my design.

The leading feature of the design consists 10 in a glove having an opening or slit extending at the side from the back edge of the glove along the wrist portion and terminating short of the hand portion, the edge of the glove at the said opening being substantially in line 15 with the side edge of the hand portion, and a flap extending along the wrist portion at the said opening, the flap projecting beyond the side edge of the hand portion and likewise terminating short of said hand portion.

20 The glove as shown has a hand portion A and a wrist portion B. From the back edge

B' of the glove an opening or slit C extends along the wrist portion B and terminates short of the hand portion A, (which therefore is not slitted,) the edge B² of the glove or of 25 the hand portion at the said opening being substantially in line with the side edge A' of the hand portion. A flap D extends along the wrist portion B at the lateral opening C, said flap projecting beyond the side edge A of the 30 hand portion, and like the opening C terminating short of the hand portion. To the wrist portion B and the flap D are secured the fastening devices E and E' respectively.

I claim—

35 The design for a glove, substantially as hereinbefore described.

PETER CHATELAIN.
